ELECTRIC SWITCH

Earnest J. Dillman, Detroit, Mich., assignor to Detroit Lubricator Company, Detroit, Mich., a corporation of Michigan

Application October 21, 1943, Serial No. 507,191

6 Claims. (Cl. 200—83)

This invention relates to new and useful improvements in electric switches and more particularly to switch operating means.

An object of the invention is to provide novel means for adjusting the operating point of the switch.

Another object is to provide means to prevent injury to the switch operating means.

Another object is to provide a switch of simple and compact construction which is efficient in operation.

The invention consists in the improved construction and combination of parts and their cooperative relation to be more fully described hereinafter and the novelty of which will be particularly pointed out and distinctly claimed.

In the accompanying drawings to be taken as a part of this specification, there are fully and clearly illustrated several preferred embodiments of the invention, in which drawings—

Fig. 1 is an enlarged view in front elevation of a switch embodying the invention and having the cover member removed and certain parts broken away to show the internal construction;

Fig. 2 is a full size view in section on the line 2—2 of Fig. 1;

Fig. 3 is a view of the switch in Fig. 1 in rear elevation;

Fig. 4 is a view in front elevation of another form of switch embodying the invention and having the cover member broken away to show the switch operating parts;

Fig. 5 is a view in side elevation of the switch of Fig. 4 and showing the cover member in section;

Fig. 6 is a rear plan view of the switch of Fig. 4, and

Fig. 7 is a detail view showing a modification with an operating range controlling spring applied to the switches of Figs. 1 and 4.

Referring to the drawings, Figs. 1 to 3 by characters of reference, 1 designates generally a housing or casing, preferably of die cast metal, having a rear wall 2 from which extends a substantially rectangular surrounding flange 3 providing top, side and bottom walls to the front face of which the cover member 4 is secured by screws 5. Projecting downward from the underside of the bottom casing wall there is a tubular extension or hollow supporting member 6 which converges inwardly downward to an internally cylindrical bore which is internally screw-threaded, as at 7. Screw-threaded into the bore 7 and sealing the same, there is a hollow plug supporting member 8 having an internal bore or passageway 9 extending longitudinally therethrough. The bore 9 is internally screw-threaded at its lower end for connection to a pressure conveying conduit or pipe leading from a switch actuating fluid pressure source. The plug 8 has a flange engaging a bore shoulder to stop its inward movement and

is locked and held in position by clamping or staking over an edge of the extension 6 against the flange, as at 10. The upper or inner end of the bore 9 within the housing 1 is closed and hermetically sealed by a resilient pressure responsive member 11, preferably a metal bellows having its open end portion extending into an annular groove or channel 12 in the upper or inner end of the member 8, in which channel the bellows member end portion is hermetically sealed and secured by solder or the like. The upwardly diverging wall of the extension 6 provides a lateral clearance for the bellows member 11. The upper end of the bellows member is closed by an end wall or head 13 having an aperture therethrough in which there is sealed and rigidly fixed an elongated supporting member 14 which extends into the bellows member 11 and above the wall 13. The member 14 has a longitudinal upward opening recess or socket 15 which is internally screw-threaded to receive adjustably a switch actuating rod or thrust member 16 which is adjustably screw-threaded in the socket 15. The member 14 has a plurality of transversely extending internally screw-threaded lock or set screw receiving bores 17 therethrough above the end wall 13, so that when the plug 8 is screwed tightly into position at least one of the bores 17 will be accessible through the front opening of the casing 1 for access to a set or lock screw 18 in the accessible bore 17 and which locks the rod 16 in longitudinally adjusted position. The rod 16 extends upward through a guide aperture 19 in the horizontal flange 20 of a guide and stop member in the form of an angle bracket having a vertical flange 21. The rod 16 may have pin receiving bores 22 for its rotated longitudinal adjustment and has its upper or inner end terminating in a stop member 23, provided by a head or downward facing shoulder engageable with the flange 20 to prevent downward pressure, either manual or otherwise, on the bellows member 11, which would change the setting or permanently stress the bellows member 11. Positioned adjacent the upper end of the rod 16 and projecting inward from the rear wall 2, there are horizontally spaced supporting bosses 24, to which there is clamped an electric switch unit 25 of any of the snap acting types stressed to one position and now on the market. The unit 25 has a supporting base or member 26 of electric insulating material clamped to the bosses 24 by screws 27 which pass through and clamp the bracket flange 21 to the bosses 24. A sheet of insulating material 28 may be clamped between the flange 21 and the bosses 24 to shield the switch unit and its terminals from the rear wall 2. Reciprocally guided through the base 26 there is a switch operating pin 29 positioned in alignment with the rod 16 and having, at its upper end, a head urged against the support 26 by a switch return leaf

spring 30. The switch has a snap acting contact 31 carried by a snap mechanism 32 actuated by the spring 30. The contact 31 cooperates with and, in the form of a switch unit shown, normally engages the fixed switch contact 33 mounted on a bracket from the base 26. The rear housing wall 2 has an opening 34 therethrough which is closed by a terminal box and lead wire conduit 35 having terminal posts 36 extending into the housing 1 and connected respectively by lead wires 37, 38 to the fixed contact 33 and the mechanism supporting the contact 31.

The operation of the switch of Figs. 1 to 3 is as follows: The rod 16 is adjusted so that the inherent resilience of the bellows member 11 will determine the fluid pressure in the member 11 at which the thrust member 16, acting through the pin 29, will move the spring 30 and mechanism 32 to snap the contact 31 away from the fixed contact 33. It will be apparent that shortening of the distance between the thrust rod head 13 and the bellows end wall 18 will increase the pressure required to operate the switch, since shortening of this distance will require a greater force to expand the bellows member 11 sufficient to actuate the switch. It should also be noted that the rod 16 can be screwed into the recess 15 so that the rod 16 is under tension, thereby further increasing the required switch actuating pressure. When the fluid pressure admitted to the bellows member through the bore 9 reaches the operating pressure for which the resilience of the bellows member 11 is set, then the head 13 will have been moved upward a sufficient distance so that the thrust rod 16 will have picked up and moved the pin 29 to its point of switch operation. When the fluid pressure within the bellows member 11 decreases so that its resilience retracts or moves downward the rod 16, then, as the pin 29 following the rod 16 frees the spring 30, the spring 30 will move the switch mechanism overcenter and the contact 31 into engagement with its fixed contact 33.

Referring to the switch of Figs. 4, 5 and 6, the numeral 50 designates a housing or casing having a rear wall 51 with top and bottom forwardly extending flanges or walls 52, 53 respectively which are joined and held in fixed relation by posts 54. The casing 50 is closed by a U-shaped cover member 55 which is secured in position by clamping screws 56 threaded into posts 57 projecting from the rear wall 51. Through the bottom wall 53 there is an aperture which is closed by a tubular plug supporting member 58 having a flange 59 which seats on the top face of the wall 53 and against which it is tightly clamped by a nut 60 screw-threaded on the member 58 and drawn up against the under face of the bottom wall 53. Supported on and hermetically closing the inner end of the bore through the plug member 58, there is a resilient pressure responsive member 61, preferably a metal bellows having its lower end portion hermetically sealed, as by solder or the like, to the flange 59. The upper or inner end of the bellows 61 is closed and sealed by an end wall or head 62 through which there is secured and sealed a supporting member 63 similar to the member 14 and in which there is screw-threaded for longitudinal adjustment a rod or thrust member 64 which extends upward through a guide aperture in the horizontal flange 65 of an angle bracket 66 which serves as a guide and stop member. The rod 64 terminates in a head or flange 67 providing a downward facing shoulder engageable with the

flange 65 to limit downward manual or other downward movement of the bellows member 65 which might permanently stress or injure the same. Positioned above the rod 64 there is an electric switch unit 68 substantially the same as the unit 25 of Fig. 1, and therefore the primes of the reference characters used in Fig. 1 designate like parts of this switch unit. The unit 68 is supported from the rear wall 51 on bolts 69 extending through spaced apertures in the base member 26' and is spaced therefrom by spacer sleeves 70 on the bolts 69. Nuts 71, threaded on the bolts 69, clamp the switch unit 68 in position and also clamp and support the vertical flange of the bracket member 66 against the rear wall 51. Secured on the outer side of the rear wall 51 there is a terminal block 72 of electric insulating material having binding posts 73 to which are secured the ends of the lead wires 37, 38' extending through insulating grommets 74 secured through the rear casing wall. The operation of this switch of Figs. 4, 5 and 6 is the same as that of Figs. 1, 2 and 3, and therefore a description of the operation is believed unnecessary.

Referring to Fig. 7, there is shown a modification of the invention applicable to the switches of Figs. 1 and 4. For convenience of exposition, the parts are designated with the suffix "a" added to the reference characters, designating like parts in Figs. 1 to 3. Screw-threaded on the rod 16a, above the member 14a, for longitudinal adjustment, there is a spring support or follower member 80. Positioned between the flange 20a and the follower member 80 and surrounding the rod 16a, there is a helical coil spring 81 held under compression and acting to urge the rod 16a downward and to collapse or compress the bellows member 11a. The force exerted by the spring 81 will accordingly be added to the force of the bellows member 11a in opposition to the fluid pressure within the bellows member 11a, so that the switch can be adjusted to operate at a range above the maximum range of switch operation afforded by the inherent resilience of the bellows member 11a. Further description is believed unnecessary, as the complete operation of this modification will be apparent from the description of the above, together with the description of Figs. 1 to 3.

What is claimed and is desired to be secured by Letters Patent of the United States is:

1. An electric switch device comprising a housing having a front wall opening, a closure member for said opening, a unitary electric switch having an operating pin and a base rigidly fixed in said housing, an inherently resilient metal bellows in said housing and having a head facing said pin, a supporting member secured in a wall aperture of said housing and supporting said bellows and having a passageway therethrough sealed by said bellows, an adjustment member carried by said bellows head and having an internally screw-threaded bore aligned with said pin, a thrust rod adjustably screw-threaded in said bore and operable to engage and move said pin to actuate said switch, means to lock said rod in adjusted position, and an apertured guide plate in said housing and rigid with said switch base and guidingly receiving said thrust rod, said rod being exposed between said plate and said bellows head through said front wall opening for adjustment, the adjustment of said thrust rod relative to said pin determining the resistance of said bellows at which said switch will be actuated.

2. An electric switch device comprising a housing having a bottom wall with an aperture therethrough, a plug member closing said aperture, said plug member having a passageway therethrough opening through its inner end, a bellows member in said housing and having one end secured and sealed to said plug member around said passageway, said bellows member having an end wall closing its other end, a supporting member extending through and sealed in said bellows member end wall and having a longitudinal internally screw-threaded socket, a thrust rod adjustably screw-threaded in said socket and extending from said bellows member, means to lock said thrust rod in adjusted position, a plate member having a vertical flange rigidly fixed to the inner rear wall of said housing and having a horizontal forwardly projecting flange with an aperture therethrough receiving and guiding said rod, a unitary electric switch having a base rigidly mounted on said rear housing wall above said horizontal flange and positioned in said housing and having an operating pin alined with and movable by said rod, and a stop member on said rod between said horizontal flange and said pin and engageable with said horizontal flange to limit collapse of said bellows member.

3. An electric switch device comprising a housing having a rear wall and having a bottom wall with an aperture therethrough, a plug member screw-threaded in said aperture and having a longitudinal passageway therethrough, means locking said plug member against rotation in said aperture, an inherently resilient bellows member within said housing and sealed to the inner end of said plug member around said passageway and having a diameter less than said plug member so that it is insertable into said housing through said aperture, said bellows member having an end wall, a supporting socket member secured in and sealing an opening through said bellows member end wall and projecting from opposite sides thereof, a thrust rod adjustably screw-threaded in said socket member, a unitary electric switch having a base rigidly mounted on said rear wall and having an operating pin alined and cooperable with said rod, a bracket member having a vertical flange secured to said rear wall and having a horizontal flange with a guide aperture receiving said rod, and a head on said rod and positioned between said pin and said bracket member horizontal flange and engageable with said bracket member horizontal flange to support said bellows against compressive force, said rod moving said pin to actuate said switch upon predetermined fluid pressure in said bellows member.

4. An electric switch device comprising a housing having a rear wall with an opening therethrough and having a bottom wall with an aperture therethrough, a terminal box and conduit fitting closing said opening, a plug member screw-threaded in said aperture and having a longitudinal passageway therethrough, means locking said plug member against rotation in said aperture, an inherently resilient bellows member in said housing and sealed to the inner end of said plug member around said passageway and having a diameter less than said plug member so that it is insertable into said housing through said aperture, said bellows member having an end wall, a supporting socket member secured in and sealing an opening through said bellows member

5 end wall and projecting from opposite sides thereof, a thrust rod adjustably screw-threaded in said socket member, a mounting member projecting into said housing above said rear wall opening and from said rear wall, a unitary electric switch having a base rigidly fixed to said mounting member and having an operating pin alined and cooperable with said rod, lead wires extending from said switch to said box, a bracket member having a vertical flange secured to said mounting member and having a horizontal flange with a guide aperture underlying said base and receiving said rod, screws clamping said base and said vertical flange to said mounting member, and a head on said rod and positioned between said pin and said bracket member horizontal flange and engageable with said bracket member horizontal flange to support said bellows against compressive force, said rod moving said pin to actuate said switch upon predetermined fluid pressure in said bellows member.

5. An electric switch device comprising a housing having a bottom wall with an aperture therethrough, a plug member closing said aperture, said plug member having a passageway therethrough opening through its inner end, a bellows member in said housing and having one end secured and sealed to said plug member around said passageway, said bellows member having an end wall closing its other end, a thrust rod carried by and extending from said bellows end wall, a follower member adjustably screw-threaded on said rod, a helical coil spring surrounding said rod and acting on said follower member to oppose expansive movement of said bellows member, a unitary electric switch having a base rigidly clamped against the interior wall of said housing and having an operating pin alined with and movable by said rod, and an abutment member holding said spring under compression and cooperable with said rod to limit collapse of said bellows member.

6. An electric switch device comprising a housing having a bottom wall with an aperture therethrough, a plug member closing said aperture, said plug member having a passageway therethrough opening through its inner end, a bellows member in said housing and having one end secured and sealed to said plug member around said passageway, said bellows member having an end wall closing its other end, a supporting member extending through and sealed in said bellows member end wall and having a longitudinal internally screw-threaded socket, a thrust rod adjustably screw-threaded in said socket and extending from said bellows member, a plate member secured in said housing and having an aperture therethrough receiving and guiding said rod, a unitary electric switch secured in said housing and having an operating pin alined with and movable by said rod, a stop member on said rod between said plate member and said pin and engageable with said plate member to limit collapse of said bellows member, a follower member adjustably screw-threaded on said rod, and a helical coil spring surrounding said rod and held under compression between said plate member and said follower member and acting to oppose expansive movement of said bellows member.

EARNEST J. DILLMAN.
